(57) **CLAIM**

The ornamental design for a holder for an edible cone, as shown and described.

DESCRIPTION

FIG. 1 is a perspective view of the present invention; FIG. 2 is a front elevation view thereof; FIG. 3 is a rear elevation view thereof; FIG. 4 is a left elevation view thereof; FIG. 5 is a right elevation view thereof; FIG. 6 is a top elevation view thereof; FIG. 7 is a bottom elevation view thereof; FIG. 8 is a perspective view of the present invention illustrating environmental structure; FIG. 9 is a perspective view of the present invention in an alternate position. FIG. 10 is a front elevation view thereof; FIG. 11 is a rear elevation view thereof; FIG. 12 is a left elevation view thereof; FIG. 13 is a right elevation view thereof; FIG. 14 is a top elevation view thereof; FIG. 15 is a bottom elevation view thereof; and, FIG. 16 is a perspective view of the present invention in an alternate position illustrating environmental structure. The broken line showing of an edible cone in FIGS. 8 and 16 is for the purpose of illustrating environmental structure and forms no part of the claimed invention.
